CLAIM

The ornamental design for a shoelace buckle, as shown and described.

DESCRIPTION

FIG. 1 is a front, right side, top perspective view of a shoelace buckle showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear, right side, bottom perspective view of the shoelace buckle when the bottom portions thereof have been pivotally moved 180° in opposite directions relative to their positions illustrated within FIG. 1.

The broken lines depict portions of the shoelace buckle that form no part of the claimed design.
